UNITED STATES PATENT OFFICE

HARRY AUERBACH, OF BROOKLYN, NEW YORK, ASSIGNOR TO ABRAHAM AUERBACH, OF BROOKLYN, NEW YORK

CONVERTIBLE PRESSER FOOT

Application filed June 8, 1931. Serial No. 542,864.

My present invention relates to attachments for sewing machines and the like and more particularly to a new and special type of that portion of a sewing machine known as the presser foot. It is the main object of the present invention to provide a presser foot which is simple in construction, easy and economical to fabricate and assemble, readily adapted for use with standard sewing machines, and which will perform a variety of functions, hereinafter set forth in detail, in an admirable manner.

In the accompanying specification I shall describe, and in the annexed drawings show, an illustrative embodiment of the attachments of the present invention. It is, however, to be clearly understood that I do not wish to be limited to the exact details shown or described inasmuch as the same may be readily varied without the exercise of the inventive faculties or departing from the spirit and scope of the claims hereto appended.

In the accompanying drawings, Fig. 1 is a side elevational view of the aforesaid illustrative embodiment of the present invention, the same being shown in a position for hemming the edge of a piece of material.

Fig. 2 is a front elevational view of the same, the piece of material being omitted so as to more clearly show the construction of the device.

Fig. 3 is a transverse sectional view taken on line 3—3 of Fig. 1.

Fig. 4 is a top plan view of the aforesaid illustrative embodiment of the present invention.

Fig. 5 is a view similar to Fig. 1 except that in this figure the device is shown in a position for gathering or shirring material.

Fig. 6 is a fragmentary perspective view of a plurality of pieces of material stitched together near the edge thereof, this view illustrating one of the products which the aforesaid illustrative embodiment of the present invention is capable of producing.

Fig. 7 is a similar view of a single piece of material having a hem formed at one edge thereof, this view illustrating another type

of work which the present invention is capable of producing.

Fig. 8 is a like view of a piece of hemmed material which is flat and to the edge of which there is sewed a border of shirred or gathered lace.

Fig. 9 is a like view of a pair of pieces of material felled or closed by means of the aforesaid illustrative embodiment of the present invention.

Fig. 10 is a similar view of a hemmed piece of material to which there is stitched a lace border; and

Fig. 11 is a like view of a piece of material one edge of which is shirred or gathered.

Before describing the aforesaid illustrative embodiment of the present invention in detail it may be desirable to briefly refer to the prior art in the field to which the present invention relates. Such presser feet as exist at present are capable of only one use, and that is, in connection with ordinary machine stitching. If it is necessary or desirable to provide a piece of material with a hem or if two pieces of material are to be felled or closed or a lace border is to be applied to a piece of material whether gathered or flat, it is necessary to carry out a plurality of separate steps and utilize a plurality of mechanisms for carrying out such steps. For example, hemming can only be done by a special hemming machine. The same applies to felling or closing. Likewise, shirring can only be done by a special machine or attachment and if it is desirable to apply a border of lace, for example, to a piece of material, it is necessary to use first a machine for hemming the material and then a separate machine for gathering and securing in place the lace border. The use of so many separate steps and mechanisms is obviously needless waste of time, energy, materials, etc. In fact, the disadvantages of such procedures are so flagrant as to make it unnecessary to discuss the same in detail in this specification.

However, all of the disadvantages of the prior art are overcome and certain advantages attained by means of the attachments of the present invention.

By means of the presser feet of the present

invention, as exemplified in the aforesaid illustrative embodiment of the same, it is possible to produce either ordinary machine stitching, hemming, felling or closing, Shirring or gathering and flat or gathered bordering, whether the main piece of material is flat, or gathered or Shirred.

Referring now more in detail to the aforesaid illustrative embodiment of the presser foot of the present invention, and with particular reference to the drawings illustrating the same, the numeral 10 generally designates an L-shaped presser foot consisting of the presser-bar-engaging portion 11 with 15 which there is integrally formed the vertical leg portion 12 terminating at the lower end thereof in the foot portion 13 which is at a right angle to the leg portion 12 and constitutes the shorter leg of the L.

20 I provide the presser foot 10 with a hemming and gathering attachment holder 14 which consists of the substantially vertical strip of material 15 carried by a screw 16 anchored in the leg 12 and presser-bar-engaging portion 11 of the foot. The screw 16 is provided with a head 17 and is receptive of a coiled expansion spring 18 which abuts the head and the vertical strip 15 so as to normally urge the latter to flatten against the 25 leg 12 of the foot 10.

The leg 12 is provided immediately below the center thereof with a threaded bore 19 which is receptive of a threaded rod 20, the front end of which engages the vertical strip 35 15 of the hemming and gathering attachment holder 14 by means of the riveted portions 21 and 22. The rear end of the rod 20 has fixed thereto a knurled knob 23 and intermediate the knob and the rear surface 40 of the leg 12, the rod carries a coiled expansion spring 24 so as to prevent the rod 20 from being too easily turned. Thus, by rotating the knob 23 to the left, the strip 15 may be drawn toward its vertical position 45 paralleling the leg 12, as shown in Fig. 5 of the drawings, and by turning said knob to the right, the strip 15 may be moved away from its vertical position, against the action of the spring 18 as shown in Fig. 1 of the 50 drawings.

Formed with the lower end of the strip 15, at a right angle thereto, is a substantially horizontal portion 25 having at one side thereof an arm 26 extending in such a manner as to present a space 27 adapted to cooperate with a cut-out portion 28 formed in the foot portion 13 so as to permit the sewing machine needle 29 to engage the material passing beneath the presser foot upon its 60 downward stroke. The arm 26 is bent at 30, similarly to a U, and terminates in a plate 31 which, as may be clearly seen from Fig. 1 of the drawings, is spaced from the arm 26. This plate, as will more fully be set forth 65 later in this specification, constitutes a gather-

ing or Shirring device and is provided with the beveled edge 32 which coincides with the beveled edge 33 formed on the foot portion 13 to present therebetween a space 34. Thus, when the vertical strip 15 is drawn toward the leg 12 of the foot 10, the gathering plate 31 is in a lower plane than the foot portion 13 at which time, as will later be described, the attachment may be utilized for gathering or Shirring. When the strip 15 is away from the leg 12, the plate 31 is in a higher plane than the foot portion 13 at which time the attachment may be used for ordinary stitching or hemming as will also later be described more in detail.

I also provide the presser foot of the present invention with a hemming and felling or closing device 35. This device consists of a plate 36 secured to the outer end of the arm 26, which plate is bent at 37 to provide the upper portion 38. The latter is bent re-entrantly at 39 so as to present the inner portion 40. Secured to the re-entrant bend 39 is a pin 41 bent at 42 to a U-shape thus presenting an inner portion 43 which is substantially equally spaced from the inner portion 40 and upper portion 38. Thus, a strip of material after passing through the hemming device 35, will be folded as shown in Fig. 3 of the drawing and will thereafter pass through space 34 intermediate the plate 31 and foot portion 13, under the latter to be stitched in its folded or hemmed position.

Finally, I provide means for guiding a strip of material or lace which is intended to be secured to the edge of a piece of material as a border for the same so as to assure the bordered material being accurately secured to the main piece of material. Such means 44 consists of a plate 45 bent at 46 to the shape of a U and terminating in a short arm 47 fastened to the underside of the plate 36. This completes the description of the aforesaid illustrative embodiment of the present invention. While the modes of using the same may be clearly understood from the foregoing description, I deem it advisable to briefly summarize the same as follows:

After the presser foot 10 is secured to the presser bar of the sewing machine, (not here shown) the device is ready for use in a plurality of ways. By rotating the knob 23, the gathering plate 31 may be rendered inoperative at which time the foot may be employed for ordinary stitching, the result being shown in Fig. 6 of the drawings. If it is desired to hem the edge of a piece of material, as shown in Fig. 7 of the drawings, the material may be passed through the hemming device 35 to fold the same as shown in the cross-sectional view of Fig. 3 after which the material passes through the space 34 and then under the foot portion 13. The same procedure is followed if it is desired 130

to close or fell two pieces of material. If it is desired to attach a border of lace or other material to the main piece of material, the latter is hemmed through the device 35 and the lace is guided by the guiding means 44 so as to meet the hemmed material emerging from the hemming device 35 immediately adjacent the needle 29 at which point the main strip of material and the lace or other border may be stitched together. If it is desired to gather or shirr the main strip of material itself or merely the lace or other border portion, the knurled knob 23 is rotated to the left so as to move the gathering device 31 into the position shown in Fig. 5 of the drawings. The lower the plane of the plate 31 with respect to the foot portion 13 the greater will be the gathering and shirring thereof. When a strip of material such as lace is guided through the guiding means 44 and then passed beneath the plate 31 and foot portion 13, the feeding mechanism of the sewing machine, (not here shown) will grip or feed only that portion of the material as is beneath the plate 31. It will not grip or feed that portion of the material which is beneath the foot portion 13 inasmuch as the foot portion is raised so that there is no cooperation between the feed mechanism and the foot portion. This causes the formation of the shirrings or gatherings. Obviously, if some cooperation is permitted between the foot portion 12 and the feed mechanism of the sewing machine, there will not be as much gathering of the material immediately in advance of the plate 31.

This completes the description of the operation of the aforesaid illustrative embodiment of the present invention. It will be noted from the foregoing that the device is simple in construction, easy and economical to fabricate and assemble, may readily be attached to standard sewing machines by merely removing the existing presser foot and substituting the present one and is adapted to carry out a multiplicity of processes in a convenient and inexpensive manner. Other superiorities and advantages of the devices of the present invention will be obvious to those skilled in the art to which the present invention relates.

What I claim as my invention is:

1. An attachment for sewing machines comprising, in combination, a presser foot, and hemming and closing means carried by said presser foot, said hemming means including a plate bent upon itself to form a short leg and having its shorter leg bent re-entrantly, and a U-shaped pin carried by the re-entrantly bent portion, one leg of which is equally spaced from said short leg and said re-entrantly bent portion.

2. An attachment for sewing machines comprising, in combination, a presser foot, and shirring means carried by said presser

foot, said shirring means including an L-shaped foot having a downwardly facing and rearwardly extending portion at the outer end thereof.

3. An attachment for sewing machines comprising, in combination, a presser foot, and shirring means carried by said presser foot, said shirring means including a resiliently carried L-shaped foot having a downwardly facing and rearwardly extending portion at the outer end thereof.

4. An attachment for sewing machines, comprising, in combination, a presser foot, shirring means carried by said presser foot, said shirring means including an L-shaped foot having a downwardly facing and rearwardly extending portion at the outer end thereof, and means to adjust said shirring means into and out of an operative position.

5. An attachment for sewing machines, comprising, in combination, a presser foot, shirring means carried by said presser foot, said shirring means including a resiliently carried L-shaped foot having a downwardly facing and rearwardly extending portion at the outer end thereof, and means to adjust said shirring means into and out of an operative position.

6. An attachment for sewing machines comprising, in combination, a presser foot, shirring means carried by said presser foot, said shirring means including an L-shaped foot having a downwardly facing and rearwardly extending portion at the outer end thereof, and an adjustable thumb screw carried by said presser foot and engageable with said shirring means to adjust the latter into and out of an operative position.

7. An attachment for sewing machines comprising, in combination, a presser foot, shirring means carried by said presser foot, said shirring means including a resiliently carried L-shaped foot having a downwardly facing and rearwardly extending portion at the outer end thereof, and an adjustable thumb screw carried by said presser foot and engageable with said shirring means to adjust the latter into and out of an operative position.

8. An attachment for sewing machines comprising, in combination, a presser foot, shirring means carried by said presser foot, said shirring means including an L-shaped foot having a downwardly facing and rearwardly extending portion at the outer end thereof and hemming and closing means carried by said shirring means, said hemming means including a plate bent upon itself to form a short leg and having its shorter leg bent re-entrantly, and a U-shaped pin carried by the re-entrantly bent portion, one leg of which is equally spaced from said short leg and said re-entrantly bent portion.

9. An attachment for sewing machines comprising, in combination, a presser foot,

shirring means carried by said presser foot, said shirring means including a resiliently carried L-shaped foot having a downwardly facing and rearwardly extending portion at the outer end thereof and hemming and closing means carried by said shirring means, said hemming means including a plate bent upon itself to form a short leg and having its shorter leg bent re-entrantly, and a U-shaped pin carried by the re-entrantly bent portion, one leg of which is equally spaced from said short leg and said re-entrantly bent portion.

10. An attachment for sewing machines comprising, in combination, a presser foot, shirring means carried by said presser foot, said shirring means including an L-shaped foot having a downwardly facing and rearwardly extending portion at the outer end thereof, hemming and closing means carried by said shirring means, said hemming means including a plate bent upon itself to form a short leg and having its shorter leg bent re-entrantly, and a U-shaped pin carried by the re-entrantly bent portion, one leg of which is equally spaced from said short leg and said re-entrantly bent portion, and an adjustable thumb screw carried by said presser foot and engaging with said shirring means to adjust the latter into and out of an operative position.

11. An attachment for sewing machines comprising, in combination, a presser foot, shirring means carried by said presser foot, said shirring means including a resiliently carried L-shaped foot having a downwardly facing and rearwardly extending portion at the outer end thereof, hemming and closing means carried by said shirring means, said hemming means including a plate bent upon itself to form a short leg and having its shorter leg bent re-entrantly, and a U-shaped pin carried by the re-entrantly bent portion, one leg of which is equally spaced from said short leg and said re-entrantly bent portion, and an adjustable thumb screw carried by said presser foot and engaging with said shirring means to adjust the latter into and out of an operative position.

15. In testimony, whereof, I have signed my name to this specification this 4th day of June, 1931.

HARRY AUERBACH.
